O. B. SUTTON ET AL
SUCTION NOZZLE WITH REMOVABLE
WAND AND ILLUMINATING MEANS
Filed Jan. 26, 1949

UNITED STATES PATENT OFFICE

2,637,062

SUCTION NOZZLE WITH REMOVABLE
WAND AND ILLUMINATING MEANSOtis B. Sutton and Warren A. Humphrey, Can-
ton, Ohio, assignors to The Hoover Company,
North Canton, Ohio, a corporation of Ohio

Application January 26, 1949, Serial No. 72,944

6 Claims. (Cl. 15—324)

1

This invention relates to suction cleaners and more particularly to those of the so-called off-the-floor type in which a suction nozzle or other air tool is connected to an air moving means by means of a flexible hose whereby the air tool may be moved about for cleaning bare floors, carpets on the floor, drapes on the wall, furniture, Venetian blinds, heating radiators, or to perform any other such household task.

The invention is applicable to suction cleaners of the so-called tank type, to upright cleaners having a converter tool and hose, or to suction cleaners of the installed system type wherein the suction creating means may be connected to installed wall ducts leading to the various rooms of a building but is particularly applicable to the first mentioned type.

It is the usual practice in the so-called off-the-floor cleaning to provide a plurality of nozzles for performing different functions. For example: for cleaning carpeted floors a suction nozzle is usually provided with a brush, comb, or other carpet pile agitating means; for cleaning bare floors a suction nozzle may be provided without a brush or with a floor polishing attachment; for cleaning furniture such as davenports, etc. a suction nozzle of a different type and having a brush may be provided; for cleaning heating radiators and other out-of-the-way places a so-called crevice tool may be provided; for cleaning Venetian blinds a special slotted tool with or without opposed brushes may be provided and many other such special tools may also be used.

Also, with suction cleaners of the tank type, blowing tools may be provided such as for blowing dust and dirt from inaccessible places, spray attachments for spraying paint or other liquids and perfume and insecticide dispensers are also frequently used.

All of these special tools have to be attached to a flexible hose, which at its other end is attached to the suction or pressure side of a motor-fan-filter unit or other air moving means.

Tools which are to be used on the floor require a long wand whereby it will be unnecessary for the operator to stoop while using such tools. Tools which are to be used on drapes, walls, or ceilings may require a short or long wand depending upon the type of work being done. Other tools such as furniture brushes or nozzles, blower nozzles, sprayers, etc., may not need any wand but merely a hand piece for manipulating the tool.

The present practice is to provide each floor tool with its own wand, special drape and wall

2

tools may be provided with shorter or longer wands as required while furniture brushes and other tools may not have any wand except a short hand grip section.

5 According to one phase of the present invention an adaptor is provided which is constructed to selectively receive any tool required. A wand is provided which may be made long or short as desired and which may be removed leaving a short hand grip section on the adaptor.

Additionally, some tools require that the wand be swivelly connected to the tool while others require that it be rigid with the hand grip portion of the adaptor.

15 According to another feature of this invention the adaptor is so made that the adaptor head is normally swiveled to the hand grip portion to which the wand is removably attached and means are provided whereby the adaptor may be locked 20 against movement relative to the hand grip portion.

25 With tools usable on floors, drapes, furniture or specially designed to clean inaccessible places it is usually desirable that the surface being cleaned be illuminated while for other operations such as perfume and disinfectant dispensing a light is not necessary.

30 According to another feature of this invention the adaptor is provided with lighting means whereby it is unnecessary to provide each tool with a separate lighting means. Additionally, a switch is provided, separate from the main cleaner switch, whereby the light may be used or not as desired depending upon the type of tool being used.

35 It is to be stressed that all of the foregoing features are embodied into the adaptor of this invention and that all of the features singly or in combination are a part of this invention.

40 Other objects and advantages of this invention will become apparent as the description proceeds when taken in connection with the accompanying drawings in which:

45 Figure 1 is a perspective view of a tank type suction cleaner with the adaptor of this invention applied thereto;

Figure 2 is a longitudinal cross-sectional view of the adaptor of this invention taken on line 2—2 of Fig. 3 with one of the many tools which may be applied thereto;

Figure 3 is a cross-sectional view taken on line 3—3 of Fig. 2; and

Figure 4 is a perspective view of the adaptor of this invention without the wand and the tool attached.

Referring to the drawings, the reference numeral 10 represents generally the adaptor of this invention. This adaptor includes a housing 11 adapted to house a lamp 12 and has laterally extending guideways 13 which interfit with channels 14 on each of the tools as will be explained in connection with the floor tool shown.

The adaptor 10 includes a hand piece 15 to which one end of a flexible hose 16 is permanently attached. The housing 11 is swiveled to the hand piece 15 in any suitable manner such as by a swivel connection 18 as shown in Fig. 2. A detent 19 of any well known construction is provided for locking the housing 11 against rotation relative to the hand piece 15 when so desired. The detent 19 is of the well known type which is normally spring-biased to locking position but which may be retracted and rotated so as to be held in unlocked position.

The light 12 is mounted in a socket carried by the hand piece 15, the housing 11 being constructed to swivel about the hand piece 15 without interfering with the light 12. The light 12 is electrically connected to conductors 20 embedded in the hose 16 by conductors 21 which are enclosed in a slot in hand piece 15 and are covered by a U-shaped sheet metal channel. The hand piece 15 is preferably made of cast aluminum or of moldable insulating material and the permanent connection between the conductors 20 and 21 may be a soldered connection or made in any well known manner.

The floor tool generally indicated by the reference numeral 25 may be of any well known construction except as modified for detachable connection to the adaptor 10. The floor tool 25, as well as each of the other selectively usable tools, has channels 14 formed therein which cooperate with the guide flanges 13 of the adaptor 10.

The floor tool 25, as well as the other selectively usable tools, has an aperture 26 which communicates with an arcuate slot 27 in the hand piece 15 so that the passage 28 in the tool is always in communication with the passage 29 in the hand piece 15 during swiveling movement of the hand piece relative to the tool 25 and also when the adaptor and hand piece are locked against relative movement.

The housing 11 is provided with the latch 30 which cooperates with a shoulder on the tool 25 and all of the other selectively usable tools for holding them in assembled relationship as the guides 13 are telescoped into the channels 14. Thus, the tool 25, or any other corresponding special tool which may be applied thereto, is swivelly connected to the hand piece 15 because the housing 11 is swiveled thereto.

A wand generally indicated by the reference numeral 35 is adapted to be detachably secured to the hand piece 15 by a screw 36. The wand 35 comprises two telescoping sections 37 and 38 and a handle portion 39 at the upper end of the section 38. The wand 35, including the sections 37 and 38, is of a channel shaped formation so as to laterally receive the hose 16. The sections 37 and 38 may be telescopically secured to each other in any suitable manner. The handle portion 39 is split longitudinally and has a portion 40 detachably secured to the handle section 39 in any suitable manner whereby the hose 16 may be removed laterally from the hand piece 15 when it is desired to detach the wand from the adaptor 10.

The hose 16 is swivelly connected at 41 to either the suction or high pressure end of a tank type cleaner generally indicated by the reference nu-

meral 45, to a converter of an upright suction cleaner or to an outlet of an installed suction cleaning system. The swivel connection 41 is of any well known electrically conducting type such as shown by Fig. 2 of the patent to Kitto 2,202,989.

The tank cleaner 45 shown has a suction end 46 and an exhaust end 47 as is well known in the art. It is also well known in the art that the hose 16 may be connected to the suction end 46 for suction cleaning or to the exhaust end 47 for blowing. Therefore, the female part of the swivel connection 41 is duplicated in the exhaust end cap 47.

The conductors 20 which are embedded in the hose 16 are electrically connected to a power source through the swivel joint 41 and switch 48 in parallel with the motor of the cleaner which is controlled by a separate switch 50. By this arrangement the motor and light 12 can be energized simultaneously when both are required or the motor alone can be energized when the light is not needed.

From the foregoing it can be seen that this invention provides an adaptor for detachably receiving any one of a plurality of air tools in which a manipulating wand is provided when necessary, in which the wand may be made long or short as necessary, in which the wand may be entirely removed when necessary, in which the tool may be swivelly connected to the hand piece or not as necessary and in which a light is provided in the adaptor which may be used or not as desired.

While we have shown and described but a single modification of our invention, it is to be understood that this modification is to be taken as illustrative only and not in a limiting sense. I do not wish to be limited to the particular structure shown and described, but to include all equivalent variations thereof except as limited by the scope of the claims.

We claim:

1. A device of the class described comprising, a flexible hose, an air conducting hand piece permanently attached to one end of said hose, an air tool, means for detachably securing said air tool to said hand piece, said hand piece and air tool having communicating air passageways, a wand for detachably receiving a portion of said hose immediately to the rear of said hand piece, said wand comprising upper and lower sections telescopically secured together, means for detachably securing the lower end of said lower section to the rear end of said hand piece independently of said hose so as to maintain air flow through said hand piece when said wand is detached and means on the upper end of said upper section for slidably receiving said hose.

2. A device according to claim 1 including means carried by said hand piece for supporting a light immediately above said air tool.

3. A device according to claim 1 in which said sections are of channel formation to partially surround said hose, said means on the upper section for slidably receiving the hose comprising a cover plate detachably secured to the upper end of said upper section so as to completely enclose said hose.

4. In a suction cleaner, a flexible hose, an air conducting hand piece connected at one end in air flow relationship to one end of said hose, an air conducting adaptor head swivelly connected at one end in air flow relationship to the other end of said hand piece, a suction nozzle connected in air flow relationship to the other end of said

adaptor head, complemental guide means on said adaptor head and said nozzle in slidable and detachable engagement with each other, coacting means on said adaptor head and said nozzle for detachably holding said guide means in complemental engagement, a wand detachably secured to said hand piece independently of said hose so that air flow relationship is maintained between said hand piece and hose when said wand is detached from said hand piece, means carried by said wand for detachably receiving and supporting a length of said hose extending along the length of said wand to the rear of said hand piece, an electrical device carried by said hand piece, and electric conductors carried by said hose and being electrically connected to said device.

5. In a suction cleaner according to claim 4 in which said device is in the form of a light above said guide means and so positioned relative thereto as to illuminate the area to be cleaned.

6. A device of the class described comprising, a flexible hose, an air conducting hand piece permanently connected at one end in air flow relationship to one end of said hose, an air conducting housing swivelly connected to the other end of said hand piece, the rear end of said housing being connected in air flow relationship to said hand piece, an air tool, complemental guide means on said housing and air tool for slidably attaching said air tool to said housing with the

10 rear end of said air tool being connected in air flow relationship with said housing, coacting latch means on said housing and air tool for detachably securing said guide means in complemental engagement, a light in the front end of said housing, conductors extending through said hand piece and into said housing for conducting electricity to said light, and a wand detachably secured to said hand piece independently of said hose so as to maintain air flow relationship between said hand piece and hose when said wand is detached from said hand piece.
